SHIRT

Frank Di Iuglio, New Haven, Conn.

Application March 18, 1943, Serial No. 479,570

2 Claims. (Cl. 2—117)

This invention relates to shirts and more particularly to men's shirts provided with means for supporting the trousers from the shirt without the employment of the usual suspenders.

As is well known, many men prefer to support their trousers from the shoulders in preference to employing a belt. On the other hand, there are certain disadvantages to the use of the common type of suspenders in that they are unsightly in appearance when a coat is not worn and they, also, are uncomfortable to some extent for most people.

One of the principal objections to the use of suspenders is their appearance. In the present invention, the unsightly appearance of suspenders is avoided but at the same time provision is made for supporting the trousers from the shoulders by means of a strap secured to the shirt itself which may be made either partly or entirely of the material of the shirt so that it will be neat in appearance and at the same time be comfortable to the wearer. Moreover, this trouser-supporting strap (or straps, as there would normally be one at each side of the shirt) is so arranged that it will give support to the trousers at the sides adjacent the hips and may be used with or without a belt as it will be practically unnoticed and if worn with a belt will give the same appearance as when the belt is worn without other support.

Moreover, these straps are secured to the shirt in such a manner that the weight of the trousers will be carried from the shoulders without undue strain on the shirt itself.

One object of the invention is the provision of a man's shirt, of novel construction, having means thereon for supporting the trousers from the shirt.

A still further object of the invention is a provision of a man's shirt having secured to the lower portion of the armhole seam a strap which depends loosely from its point of secured and which is provided at its lower end with means by which it may be secured to a trouser button to support the trousers.

Still another object of the invention is the provision of a man's shirt with a trouser-supporting strap secured at its upper end to the lower portion of the armhole seam of the shirt at the inside of the latter, which strap is carried outwardly through an opening in the shirt so that the end of the strap may be readily secured to a trouser button or the like. The opening through which the strap is carried being so made that the strap will have free sliding movement relatively

to the shirt itself so as not to adversely affect the appearance of the latter.

To these and other ends, the invention consists in the novel features and combination of parts 5 to be hereinafter described and claimed.

In the accompanying drawing:

Fig. 1 is a side elevational view of a shirt embodying my invention;

Fig. 2 is a view of the inside surface of the 10 shirt shown in Fig. 1;

Fig. 3 is a sectional view on the line 3—3 of Fig. 2; and

Figs. 4 and 5 are views similar to Fig. 2 showing modified forms of the invention.

To illustrate a preferred embodiment of my invention, I have shown in Figs. 1 to 3 of the drawing a shirt having a body portion 10 to which is secured the usual sleeve 11 by means of stitching at the armhole 12, the shirt being provided with the usual side-seam 13.

As shown in Fig. 2 of the drawing, a suspender strap 14 is secured at the side of the shirt by having its upper end stitched in the armhole seam 12, as shown at 15. It may be noted that the strap 14 is larger at its upper end than at the lower end so that it will provide an extended or elongated surface for stitching to the armhole seam. This will serve to spread the strain carried by the strap 14 and will insure a secure connection of the strap with the shirt at its upper end without undue bulkiness. It may also be noted that, as shown in Figs. 1 and 2, the strap 14 is disposed slightly forwardly of the side seam 13 so that the pull upon the armhole seam 12 will be slightly forward of this side seam and will tend to be carried by the front of the shoulder portion of the shirt rather than the back.

As shown in Figs. 1 to 3, the front portion of the shirt at a point adjacent the armhole seam 40 and spaced from the secured portion 15 of the strap 14 is provided with an opening 16 through which the strap 14 may be carried to the outside of the shirt. This lower exposed end of the strap may be provided with button holes or the like, 45 17, for engagement with a trouser button, the holes 17 being spaced along the length of the strap.

Embracing the portion of the garment in which the opening 16 is formed is a piece of reinforcing material 18 which may be the same material as the shirt itself, and it will be noted that the base or rear end of this material is stitched into the side seam as shown at 19 and the edge of this material is likewise stitched to the shirt as shown 55 at 20. It will, of course, be understood that the

opening 16 is formed through the reinforcing strip 18 as well as being formed in the material of the shirt itself, so that the strap may be carried through the shirt as shown in Fig. 3. The reinforcement 18 not only gives added strength to the shirt about the opening so as to prevent the tearing out or fraying of the latter but also tends to tie the strap 14 to the side seam of the shirt and thereby hold the strap in place.

It will be understood that the strap 14 normally will be secured only at its upper end at point 15 and will depend loosely from this point. If it is desired to use this strap in supporting the trousers, the lower end will be carried to the outside of the shirt through the opening 16. If, however, it is not desired to make use of the strap 14, it may hang within the shirt and not be passed through the opening 16. In that event, this opening will normally be covered by the sleeve and the shirt will have the appearance of the ordinary shirt without any trouser supporting strap. The opening 16 will, of course, be made of such length as to permit the strap to slide freely therethrough although when the shirt is worn and the strap is secured to the trousers there will be little relative movement between the strap and the adjacent portions of the shirt.

Strap 14, as stated, may be made of the same material as the shirt itself so as not to be conspicuous. If desired, it may be made of fused material so as to be relatively stiff and, ordinarily, it will be made of a plurality of plies of material so as to be of sufficient strength.

If desired, however, this strap may be made partly or wholly of elastic material. For example, in Fig. 4 of the drawing a strap is shown in which the upper part 14^a is of non-elastic fabric; the middle portion, 14^b, of elastic fabric and the lower portion, 14^c, of inelastic material. This, of course, may be varied as desired and any portion of the strap may be made of elastic material.

In Fig. 5 of the drawing, I have shown a somewhat modified form of my invention wherein the strap 14 is not provided with openings 17 but instead has secured to its exposed end a suspender buckle 22 carrying suspender tabs 23 for attachment to the buttons of the trousers. It will be understood, of course, that the buckle 22 will be adjustably secured to the strap 14 so that it may be moved upwardly and downwardly to suit the convenience of the wearer. In this modification of my invention, the strap 14 may be made wholly or partly of elastic material or it may be made entirely of inelastic material and, if desired, the suspender tabs 23 may be made of elastic ma-

terial. In other respects, the form of my invention shown in Fig. 5 of the drawing is the same as shown in Figs. 1 to 3.

It will be obvious that I have provided a shirt with a trouser-supporting strap permanently secured thereto, which strap will efficiently serve the purpose for which it is intended and at the same time will not be unsightly or inconvenient or uncomfortable to the wearer.

While I have shown and described a preferred embodiment of my invention, it will be understood that it is not to be limited to all of the details shown but is capable of modification and variation within the spirit of the invention and within the scope of the claims.

What I claim is:

1. A shirt having side seams extending downwardly from the armholes, a strap at the inside of the shirt at each side thereof below the armholes each of said straps being secured at the upper end to the armhole seam forwardly of the junction of the side seams therewith and hanging downwardly therefrom, the shirt being provided with openings adjacent to, but spaced forwardly from, the side seams and at points spaced a considerable distance below the armholes through which said straps extend to the outside of the shirt, fastening means on the lower end of said straps for connection with a trouser button, and reinforcing pieces of material surrounding said openings extending rearwardly to and secured in said side seams.

2. A shirt having side seams extending downwardly from the armholes, a strap at the inside of the shirt at each side thereof below the armholes each of said straps being secured at the upper end to the armhole seam forwardly of the junction of the side seams therewith and hanging downwardly therefrom, the shirt being provided with openings adjacent to, but spaced forwardly from, the side seams and at points spaced below the armholes through which said straps extend to the outside of the shirt, fastening means on the lower end of said straps for connection with a trouser button, said straps being wider at their upper ends than at the lower ends whereby they may be stitched to the armhole seam over an extended area and reinforcing pieces of material surrounding said openings and extending rearwardly to, and secured in, said side seams, said pieces being of a relatively narrow vertical dimension and being spaced below the armholes.

FRANK DI IUGLIO.
